ELECTROMAGNETIC CORE

Erwin E. Franz, Cranford, N. J., assignor to
 Western Electric Company, Incorporated, New
 York, N. Y., a corporation of New York

Application December 9, 1938, Serial No. 244,729

6 Claims. (Cl. 175—21)

This invention relates to electromagnetic coils and more particularly to electromagnetic coils having laminated cores assembled from sheet metal elements.

5 Coils are used in an endless variety of forms and ways in electrical apparatus, and generally speaking fall into two great classes, coreless coils and cored coils in which the windings surround cores of magnetic material. Cored coils very frequently are made with cores built up from assembled laminae of sheet material, in order to diminish energy waste due to eddy currents in the body of the core. Much ingenuity has been expended upon ways of manufacturing such laminated cores in order that the making of the cores and the assembling of the cores and their windings may be as simple, cheap and wasteless as possible. For various reasons difficulties have been encountered. Coils have been produced satisfactorily with cores which are wasteless in production, but with which the winding must be pre-wound on a spool or other support and then installed bodily upon the assembled or partly assembled core. In such structures space is taken up and wasted so far as the efficiency of the coil is concerned by the spool or support on which the coil is wound. Other laminated core coils have been produced in which the winding of the conductor has been done directly on the assembled or partly assembled core without the need of any special winding spool or frame. However, in many instances the laminae for assembling such cores cannot be produced wastelessly. Furthermore, in cases where the core is assembled in a prewound winding, the mechanical working of the laminar core material when the laminae are clamped or riveted together may seriously damage the magnetic properties of a core made of some of the recent high permeability alloys; and such cores cannot be then annealed to restore the desired properties with the insulated windings in place on them.

An object of the present invention is to provide a coil structure and a laminated core for a coil which shall present a coil having a core and winding combinable substantially without any electrically useless winding spool, frame, or the like, in which the laminar core is composed of 50 elements produced from sheet material in which a considerable range of ratio of winding volume to core is possible, which is adaptable equally to such constructions as shell type and core type transformers among others, and in which the core is so constructed that no working of the core

material is required after the windings are installed.

With the above and other objects in view, a typical embodiment of the invention may comprise a coil having a core built up of layers, each 5 layer consisting of two or more equally tall flat pieces punched or otherwise formed from magnetic sheet material, of which pieces one outer one may be a short armed C, the middle piece an H lying on its side and having long arms abutting the arms of the short armed C and short arms on its other side, and another outer piece a long armed C whose arms abut the short arms of the middle piece. In other forms, the H-shaped piece may be omitted, or itself comprise 10 two C-shaped pieces.

Other objects and features of the invention will appear from the following detailed description of embodiments thereof taken in connection with the accompanying drawings in which the 20 same reference numerals are applied to identical parts in the several figures and in which—

Fig. 1 is a diagrammatic view of a strip of magnetic sheet material to show the wasteless production of core lamina parts therefrom; 25

Fig. 2 is a plan view of a core composed of the laminar parts of Fig. 1;

Fig. 3 is an enlarged sectional view on the line 3—3 of Fig. 2;

Fig. 4 is a plan view of a coil wound on the core 30 shown in Fig. 2;

Fig. 5 is a view similar to Fig. 1 of a modified form;

Fig. 6 is a view thereof corresponding to Fig. 2;

Fig. 7 is a view similar to Fig. 1 of another 35 modified form;

Fig. 8 is a view thereof corresponding to Fig. 2;

Fig. 9 is a view similar to Fig. 1 of a third modified form;

Fig. 10 is a view thereof corresponding to 40 Fig. 2;

Fig. 11 is a view thereof corresponding to Fig. 3;

Fig. 12 is a view corresponding to Fig. 1 of a 45 fourth modified form;

Fig. 13 is a view thereof corresponding to Fig. 2.

Fig. 1 may be thought of as a ribbon of magnetic sheet material from which laminar pieces are to be cut for subsequent assembly into units of an electrical coil core, and on which the pieces 50 are laid out to show how they may be cut from a parallel sided ribbon substantially without scrap or waste. There are three kinds of pieces shown, viz. C-shaped pieces indicated at 20 having relatively long arms 21, C-shaped pieces indicated at 55

22 having relatively short arms 23, and H-shaped pieces indicated at 24 having relatively long arms 25 on one side and relatively short arms 27 on the other side. The C-shaped pieces of both kinds have holes 26, through which assembling rivets 30 are to be passed later, in the centers of the backs of the C's, midway of both the length and width of the backs of the C's. The H-shaped pieces have similar holes 28 near each end located at the two intersections of the axis of the crossbar of the H with the two axes of the arms. It will be noted that the adjacent long arms 25 of any two neighboring H's are enclosed within and exactly fill the recess of a C 20, that adjacent long arms 21 of any two neighboring C's 20 are enclosed within and exactly fill the recess between long arms 25 of an H, that the adjacent short arms 27 of any two neighboring H's are enclosed within and exactly fill the recess of a C 22, and that adjacent short arms 23 of any two neighboring C's 22 are enclosed within and exactly fill the recess between short arms 27 of an H. Hence there is no scrap or waste when the pieces shown are punched or otherwise cut from the ribbon except the insignificant and unavoidable scrap or chips from the punching or drilling of the holes 26.

The three kinds of pieces shown in Fig. 1 having been prepared in sufficient number, are assembled by stacking and riveting into the three units shown in Fig. 2 at 31, 32 and 33, respectively. The unit 31 is a stack of the two kinds of C-shaped pieces, 20 and 22, piled in alternation, a 22 at the top followed by a 20 and a 22 and a 20 and so on downward, with their arms in congruence, i. e. all on the same side and each arm lying exactly against another arm so far as their lengths permit. This stacked unit 31 is substantially smooth on all faces except at the ends of its two arms or extensions to the right where the alternation of short arms 23 and long arms 21 presents a series of recesses at the ends of the short arms between the projecting long arms.

The unit 33 is identical in form and structure to the unit 31, except that the pile begins at the top with a C 20.

The unit 32 is a pile of H-shaped pieces only laid with the crossbars 29 in superimposed congruence and the long and short arms extending alternately to the left and right. This stack or unit 32 has all of its surfaces substantially smooth except the four extremities of its arms, which are recessed to correspond on one side to the projections between the recesses of the arms of the unit 31 and on the other to those of the unit 33.

The three stacks having been piled as described independently of each other, may be riveted, respectively, with rivets 30, or otherwise bound to form rigid units.

60 The material of the core pieces 20, 22 and 24 in some instances will preferably be of silicon steel or of one or another of the high permeability nickel iron alloys known as permalloy. These materials may be given an extremely high permeability, or retentivity, or low hysteresis, or other desirable electromagnetic character by appropriate heat treatment. These materials, however, are extremely sensitive to mechanical working, or even shock, after having been so heat treated; and any slight working, such as that caused by the seating and swedging over of the rivets 30 in the present instance, may seriously impair the particular characteristic of the material.

75 In employing the present invention therefor,

the heat treatment is deferred until the three units, 31, 32 and 33 are individually complete as described, i. e. stacked and riveted, since, according to the invention, no further working or straining of the material of the cores need then occur.

To make such a coil as is shown in Fig. 4, it is then only necessary to wind the unit 32 and assemble the three units. The winding space between the arms of the H-shaped unit 32 is completely unobstructed. The winding of the insulated conductor may be done by hand or, preferably, by any suitable winding machine, until the requisite number of turns is in place on the unit 32. The units 31 and 33 are then assembled with the unit 32 to embrace the winding as shown in Fig. 4 and to have the relations to the unit 32 best shown in Figs. 2 and 3.

The complete core, shown in Figs. 2 and 3 without the winding 34, consists essentially of 20 successive layers, each layer consisting of one H-shaped piece and two unlike C-shaped pieces. The top layer as shown has a C 22 at the left, the ends of whose short arms 23 abut directly against the ends of the long arms 25 of an H 24. The ends of the short arms 27 of the H 24 abut directly against the ends of the long arms 21 of a C 20. The second layer has identically similar elements but in reverse order. Every odd numbered layer is identically like the first, and every even numbered layer like the second. From this it follows that the division between the units 31 and 32 or between the units 32 and 33 is not a substantially smooth plane, but is a square angled zigzag with elements of one unit overlapping elements of the other by an amount equal to the difference in length of 23 and 21. This zigzag overlapping at the joints brings two desirable results. First, the gap reluctance of the assembled core's magnetic paths at the joints of the 40 units is materially diminished as compared with a core where the corresponding joint is a plane face and there is no lateral contact between parts of the units. Secondly, the interfitting of the projections and recesses of the units provides a 45 modicum of mechanical support of the units by each other and of frictional resistance to separation of the units, which renders the assembled core or coil much easier to handle and mount, due regard being had to the sensitivitity of the 50 material to shock or deformation.

It is also of importance that the H-shaped unit 32 offers no obstruction to the winding of the coil turns 34. Hence the coil need not be pre-wound on a spool, frame or other support for 55 subsequent assembly with a core unit, as is the case, for example, with a coil core generally similar to that of Figs. 1 to 4 but composed of E-shaped pieces with a straight bar across the open side of each E. Hence, as clearly shown in Fig. 4, the entire cross section of each of the apertures or "windows" of the core is available to be filled with windings, as none of the window space need be wasted either to receive an electromagnetic inoperative winding spool or frame, 65 or by clearance oversize internally and undersize externally of a prewound coil formed with adhesive or other means to maintain its form while being assembled on the core.

The core shown in Figs. 1 to 4 has the maximum symmetry in all ways possible to this mode of construction. The windows are square, the bar of the H is of the same shape and size as the windows, and each side of a window not made by the crossbar is the same size and shape as half 75

the crossbar or window. The core cross section of the magnetic path is the same throughout, assuming that the flux divides equally on leaving the crossbar to pass around the two windows.

5 Figs. 5 and 6 correspond in every way, respectively, to Figs. 1 and 2 except that the proportions of the C's, 520 and 522, and of the H's, 524, are such that the windows are lengthened transversely to the crossbar and the magnetic path is 10 diminished in cross section. The ratio of magnetic material to conductor material is substantially diminished.

10 Figs. 7 and 8, corresponding, respectively, to Figs. 1 and 2, are presented to show in one embodiment both how the windows may be shortened transversely to the crossbar and the magnetic path increased in cross section and how the magnetic path may be unbalanced if desired for any reason by altering the proportions of 15 the C's, 720 and 722, and of the H's, 724.

In both Figs. 5 and 7, however, the scraplessness of Fig. 1 is retained, as is the overlapping interfitting of the three units in each case also.

20 To effect this interfitting so that not only will the interfitting occur, but also all faces of each unit except the interfittable ends of the arms shall be substantially smooth, the following conditions are believed, from a study of Figs. 1, 5 and 7, to be necessary and sufficient. The widths 25 KM and WN of the backs of the C-shaped pieces must be equal. The widths JQ and AG of the C arms must be equal as also the widths GR and QP of the C arms. The widths KZ and WS of the H arms must be equal as also the widths SD 30 and ZB of the H arms. And the lengths DJ and AB of the C arms must be unequal as also the lengths DJ and AB of the H arms. Finally, the widths SD and GR as also the widths WS and AG of the H arms and C arms to be abutted in 35 one layer of the core, must be respectively equal.

To effect the scrapless production of the parts in the manner shown in Figs. 1, 5 and 7, it is necessary and sufficient that: The sums of the widths JQ and QP and of the widths AG and GR 40 of the upper and lower C's, respectively, be equal to the distances JP and AR between the arms on the corresponding side of the H; the sums of the widths KZ and ZB and of the widths WS and SD of the arms of the H respectively must be 45 equal to the distances KB and WD, respectively, between the arms of each corresponding C; and the lengths AB and JD of the H arms must be 50 respectively equal to the lengths AB and JD of the C arms.

55 In Figs. 9, 10 and 11 is shown a manner in which substantially the same result is achieved by the use of C-shaped pieces only. Fig. 9 represents, in effect, the ribbon shown in Fig. 1 separated longitudinally into two ribbons along a 60 line lying above the center of the ribbon of Fig. 1, and with the central row of perforations 26 replaced by two rows, one in each ribbon of Fig. 9. The C-shaped pieces 20 and 22 of Fig. 9 are identical with 20 and 22, respectively, of Fig. 1 in 65 form. Each H-shaped piece 24 of Fig. 1, however, is now split into or replaced by two C-shaped pieces 124 and 224. Figs. 10 and 11 show how a laminar core is assembled from these pieces with four pieces, one of each kind, in each layer 70 and forming four units. Units 31 and 33 are identical with units 31 and 33 of Fig. 2 in form and structure, but unit 32 of Fig. 2 is split into or replaced by two units 132 and 232 in Fig. 10. Units 132 and 232 put together are substantially 75 identical in form with unit 32.

In making a coil like that of Fig. 4 but with a core like that of Fig. 10, units 132 and 232 are first stacked and riveted independently of each other and heat treated and then assembled together into one H-shaped unit by interfitting the backs of the C-shaped pieces of which each is composed. Such an object has sufficient stability and coherence by virtue of this interfitting to permit of being handled as a single unit while the winding is being put on as in the case of the coil 10 of Fig. 4. Then, as before, the winding being finished, the units 31 and 33 are assembled with the wound central unit.

In Figs. 12 and 13 there is shown a coil structure based on the same general principles, although the shapes of the pieces are superficially different, and to attain the same general results. Here the central unit 332 consists of stacked H-shaped pieces with the ends of the arms formed with notches 35, and with long arms 36 alternating with short arms 37 around the H. In the unit 332, these H-shaped pieces are stacked with long and short arms alternating over each other.

In cutting the various pieces, of which there are only two kinds, as shown in Fig. 12, a set 25 of four perforations 26 is first punched in the strip or ribbon at an operating station indicated at I. At station II an L-shaped piece 320 is punched out. At station III a second L-shaped piece 322 is punched out, and at station IV the 30 H-shaped piece 324 is cut off.

The two L-shaped pieces are identically alike and interchangeable in assembly. Each is formed and proportioned to have the notched top of its long arm abut and fit accurately into notch 35 35 of either long arm 36 of the H-shaped pieces while its short arm extends into and fits the notch 35 of the short arm of the H on the same side. These L-shaped pieces are stacked in the units 331 and 333 with their short arms alternately at each end of the unit but all on the same side of the unit, thus creating a substantially C-shaped unit to combine with the central H-shaped unit as in the previous constructions.

The unit 332 may then be wound as in the preceding cases and the units 331 and 333 assembled therewith in the same manner, to interfit in substantially the same way, at the corners of the assembled core.

In another variation of the invention, if smooth butt joints between the units 31, 32 and 33 of Fig. 2 be desired, the units 31 and 33 may be composed only of C 22 or of C 20 pieces, respectively, and the H's in unit 32 may be stacked with their 55 long arms all on the same side. The vertical faces of the ends of the arms of all three units will then be substantially smooth and the units may then be abutted without interfitting. Such a structure with coils on all three units could 60 then be used wherever variable inductive coupling between coils is desired by separating or approximating the wound units.

The embodiments of the invention herein disclosed are illustrative and in their variety show 65 that they may be modified and departed from in many ways without departing from the spirit and scope of the invention as pointed out in and limited solely by the appended claims.

Certain subject matter shown but not claimed 70 in this application is claimed in my divisional application S. N. 338,060.

What is claimed is:

1. A laminated electromagnetic core comprising a plurality of laminae of magnetic material piled 75
